Patented Feb. 3, 1976

238,657

BOTTLE CARRIER

Gerald Erickson, P.O. Box 6175, Surfside, Fla. 33154

Filed May 22, 1974, Ser. No. 472,087

Term of patent 14 years

Int. Cl. D9—99

U.S. Cl. D9—178

FIG. 1

FIG. 2

FIG. 3

FIG. 4

FIG. 5

FIG. 1 is a plan view of a bottle carrier embodying my new design;

FIG. 2 is a bottom view;

FIG. 3 is a view taken along the line 3—3 of FIG. 1 looking in the direction of the arrows;

FIG. 4 is an end view; and

FIG. 5 is a view taken along the line 5—5 of FIG. 1 looking in the direction of the arrows.

I claim:

The ornamental design for a bottle carrier, as shown.
